DESIGN FOR A GLOVE

Evelyn Webster, Gloversville, N. Y.

Application February 21, 1938, Serial No. 75,322

Term of patent 7 years

To all whom it may concern:

Be it known that I, Evelyn Webster, a citizen of the United States of America, residing in Gloversville, county of Fulton, and State of New York, have invented a new, original, and ornamental Design for a Glove, of which the following is a specification, reference being had to the accompanying drawing, forming part thereof, wherein,

The characteristic feature of my design resides in the combination of the buttons and the contrasting strips arranged on the glove as shown.

I claim:

The ornamental design for a glove, substantially as shown and described.

EVELYN WEBSTER.
